SUCTION NOZZLE

Guy A. Yedd, Oakland, Calif., assignor of one-half to John R. Pusey, Oakland, Calif.

Application March 7, 1933, Serial No. 659,935

7 Claims. (Cl. 262—2)

The invention relates to a nozzle for use in hydraulic mining.

An object of the invention is to provide a suction nozzle which is particularly adapted for use in the mining art for removing deposits from basins or crevices in bedrock.

Another object of the invention is to provide a suction nozzle which is operable as an oscillating drill or reamer for gaining access to material to be removed through the nozzle.

Yet another object is to provide for an impact actuation of the nozzle during its aforesaid use as a drill or reamer.

An added object is to provide a nozzle of the character described which is particularly adapted for direct manual manipulation and control by a diver at its point of use.

The invention possesses other objects and features of advantage, some of which, with the foregoing, will be set forth or be apparent in the following description of a typical embodiment thereof, and in the accompanying drawing in which,

Figure 1 is a side view of a nozzle embodying the invention.

Figure 2 is a section at 2—2 in Figure 1.

Figure 3 is an enlarged section at 3—3 in Figure 1.

Figure 4 is an enlarged perspective view of a closure member of the structure.

Figure 5 is a longitudinal and axial section of the nozzle.

Figures 6 and 7 are enlarged side and end views of a tip member of the nozzle.

Figure 8 discloses the nozzle in operative association with a pneumatic hammer and as being applied by a diver to a submerged deposit.

The present nozzle assembly is that which is disclosed in lesser detail in my copending application, Ser. No. 659,934, for United States Letters Patent on a Mining system and apparatus. As illustrated, the disclosed nozzle 11 essentially comprises a shaft 12 terminating in a removable tip 13 and provided with an interior longitudinal

duct 14 for connection with a suction hose line 15 of a pump (not shown), said duct receiving material through hereinafter described end and side openings of the nozzle shaft.

Adjacent its upper end, the nozzle shaft carries a collector head 16, said head being formed in the present instance as a hollow rectangular box having aligned openings 17 for sealedly receiving the shaft 12 therethrough, as particularly shown, stuffing boxes 18 are provided at the openings 17 for sealing the openings and

securing the box 16 in fixed position on the shaft. A nipple 19 is threadedly engaged through an opening 21 in a side wall of the box for providing a connection with the suction hose 15, and a clean-out plug 22 is provided in an opening 23 in the opposite box wall. Preferably, and as shown, the plug 22 carries a handle 24, it being noted that this handle and the hose portion at the nipple 19 provides means whereby an operator may hold and manipulate the nozzle as may be required during its working application. In the present instance, the shaft 12 is of uniform cross-section and the duct 14 extends axially therethrough from a point opposite the box 16 to the bit end of the shaft. Radial ports 25 are provided through the tubular portion of the shaft at the box 16 whereby the duct 14 may discharge into the box space about the shaft and so into the suction hose 15.

The tip 13, it will now be noted, comprises a tubular base portion 26 which is threadedly engaged within the open end of the shaft 12 and provides a continuation of the duct 14. The exposed portion of the present tip 13 is generally pyramidal in outline and the faces thereof are provided with concavities 28 from the bottoms of which passages or ports 29 extend inwardly to the duct 14; in this manner, the tip 13 is understood to comprise a suction nose for the nozzle. It is noted that the faces of the tip portion 27 intersect at relatively sharp edges 31 whereby the tip portion 27 generally comprises a conical reamer.

The portion of the shaft 12 between the head 16 and the tip 13 is externally formed with a series of longitudinal grooves 32 symmetrically arranged about the shaft whereby the grooved shaft portion resembles a cylindrical reamer. Ports 33 extend into the shaft duct 14 from the inner sides of the grooves 32, said ports spaced apart in the grooves and spirally aligned about the shaft whereby they provide a succession of inlets to the duct 14 varying distances from the nozzle tips.

During a working application of the nozzle, it is generally desirable that only those ports 33 be open which are adjacent material to be moved, and to this end individual closure members 34 are provided for application at the ports to be closed. As particularly illustrated, the grooves 32 are of uniform cross-section longitudinally thereof and are widest at their bottoms whereby they are generally trapezoidal in cross-section, while the closure members 34 comprise blocks or plates of like section for retention in the grooves 35.

against lateral removal from the shaft while 5 slideable in the grooves. Setscrews 35 are threadedly engaged in the closure blocks 34 radially of the shaft for forcible engagement with the groove bottom for releasably securing the blocks in fixed position in the grooves whereby said blocks may be set and fixed in either operative or inoperative relation to the ports 33.

In the present instance, the heads of the set-screws 35 are countersunk in the blocks 34, while the screw tips are arranged to engage in sockets or depressions provided in the inner wall of the groove at appropriate points thereof. When a port 33 is to be open, the corresponding closure member 34 is arranged to be held and disposed immediately above the port in the relation disclosed in Figures 1 and 5; in this manner, the lower and outer block edges may be operative as cutters against material contacted by them, 20 said edges being sharpened if desired.

Preferably, and as shown, the upper end portion of the nozzle shaft 12 is formed for mounted insertion in the chuck 36 of a pneumatic hammer 31, said hammer of an impact type now used to 25 actuate rock drills and digger tools and other types of bits requiring a hammering actuation thereof. A hose 38 conveys actuating air to the hammer, while the exhaust air from the hammer is preferably discharged at the surface of the 30 body of water in which the nozzle is used through a hose 39 terminating at a float 41. The aforesaid disposition of the exhaust air from the hammer 31 prevents any interference of bubbles or air discharge with the operations of a diver 42 35 applying the nozzle under water, as is illustrated in Figure 8.

It will now be noted that in applying the nozzle under water, the diver may insert the suction tip 13 in a crevice 43 or in a "pot hole" 44 or in 40 other depressions or basins containing deposits of heavier materials which may be expected to include particles of precious metals such as gold or platinum. Since the diver directly handles the nozzle, he may dispose the same at the proper 45 location and angle for greatest efficiency of operation. For working in a crevice or beside a deposit to be removed, appropriate side ports 33 would be opened. If the particles of the material to be removed are mutually adherent for 50 preventing a suction removal thereof, the same may usually be mutually separated by oscillating the nozzle in its place for loosening the material of the deposit.

For deposits which are hard packed and in 55 "crevicing" with the nozzle, the hammer 31 would be energized whereby a power drilling may be effected as the nozzle is oscillated by the diver. By the use of the side ports 33, all material loosened as the nozzle progresses through a deposit toward the bottom of a crevice or bedrock 60 hole is removed through the nozzle. While the present device is primarily designed for use in placer mining, it is noted that the described drilling and reaming features are operative for 65 effecting the removal of material from submerged veins or lodes containing precious metals, at least to an exploratory degree. It will, of course, be obvious that other types of suction tips than that shown may be used with the nozzle for meeting special operative conditions.

In view of the foregoing, it will be understood 70 that the diver may apply the nozzle of present invention either with or without effecting a manual oscillation thereof, or with or without an actuation of the pneumatic hammer. Further-

more, the nozzle may be used and applied without any association thereof with a hammer means, the disclosed association being generally preferable however, since the diver is thereby prepared to meet a maximum number of situations as he explores and works a stream bed with the nozzle. Since a stream bed may contain boulders which cover deposits to be removed, the shaft 12 is preferably of appropriate length and strength for use as a pry-bar, such use of the 10 nozzle being indicated in Figure 8.

From the foregoing description taken in connection with the accompanying drawing, the advantages of the construction and method of operation will be readily understood by those 15 skilled in the art to which the invention appertains, and while I have described the principle of operation, together with a device which I now consider to be a preferred embodiment thereof, I desire to have it understood that the device 20 shown is merely illustrative, and that such changes may be made, when desired, as fall within the scope of the appended claims.

Having now described my invention, I claim as new and desire to secure by Letters Patent of 25 the United States the following:

1. In an hydraulic suction nozzle, a tubular shaft having a longitudinal external groove therein, a port connecting said groove with the duct of the shaft, a closure member for said port engaged entirely in said groove, and means to fix said closure member in either operative or inoperative relation to said port while disposed in the groove.

2. In an hydraulic suction nozzle, a tubular shaft having a longitudinal external groove of uniform cross-section therein, said groove widest at its inner side, a port connecting the inner side of the groove with the duct of the shaft, a closure member for said port slidably engaged in said groove, said member of complementary cross-section to the groove, and a set-screw engaged in said member and operative against the shaft at the inner side of said groove to releasably fix the member therein in adjusted relation to said port.

3. In a suction line nozzle of the class described, a tubular shaft having a longitudinal external groove therein whereby the shaft portion thereof is generally operative as a reamer, 50 a port connecting said groove with the duct of the shaft, a closure member for said port slidably engaged in said groove, and means to fix said closure member in either operative or inoperative relation to said port.

4. In a drilling tool of the character described, a tubular shaft having a longitudinal external groove therein whereby said shaft is generally operative as a reamer, a plurality of mutually spaced ports connecting the bottom of said 60 groove with the duct of the shaft, and means operative within the confines of the shaft to independently close selected said ports.

5. In a drilling tool of the character described, a tubular shaft having a plurality of longitudinal external grooves therein whereby said shaft is generally operative as a reamer, ports extending from said grooves to the duct of the shaft and at varying distances from the forward shaft end whereby said ports define a line thereof extending spirally around the shaft, and means operative within the confines of the shaft to independently and selectively close one or more of said ports.

6. In a drilling tool of the class described, a 75

tubular shaft having a longitudinal external groove of uniform cross-section therein, a port connecting the groove with the duct of the shaft, a closure member for said port engaged 5 in and adjustable along said groove, said member of complementary cross-section to the groove and provided with a free cutting edge at the juncture of its outer face with an end face thereof, and means cooperative between the 10 shaft and the closure member to fix the latter in either operative or inoperative relation to said port while it is disposed in said groove.

7. An hydraulic suction line nozzle comprising a tubular shaft of uniform circular cross-section terminating at a boring bit for providing a bore no larger than the shaft, said shaft having a longitudinal groove therein terminating at said bit whereby said shaft is arranged to be generally operative as a reamer in a bore provided by the bit, and a plurality of mutually spaced ports connecting the bottom of said grooves with the duct of the shaft. 5

GUY A. YEDD. 10
